Specification of Letters Patent.

Patented May 2, 1911.

Application filed February 21, 1910. Serial No. 544,962.

To all whom it may concern:

Be it known that I, ALBERT H. ACKERMAN, a citizen of the United States, residing at Chicago, in the county of Cook and State 5 of Illinois, have invented a certain new and useful Improvement in Brushes, of which the following is a specification.

This invention relates to shaving brushes, and has for its object to provide a new and 10 improved brush of this description.

The invention is illustrated in the accompanying drawings, wherein—

Figure 1 is a sectional view showing a brush embodying the invention; Fig. 2 is a 15 view showing the brush in position to discharge liquid into the bristles; Fig. 3 is a view taken on line 3—3 of Fig. 1; Fig. 4 is a view taken on line 4—4 of Fig. 1.

Like letters refer to like parts throughout 20 the several figures.

In the drawings I have shown a brush provided with the bristles A and the hollow handle B. The bristles and the handle are relatively movable. A cylinder or receptacle 25 C is associated with both the handle and the bristles. As herein shown the receptacle C is connected with the bristles and is movably mounted in the handle so that it may be moved back and forth therein. A piston D 30 is connected to the handle in any desired manner, as by means of the supports E. One or more ports F are formed in the receptacle C and these ports are normally closed by the piston D (see Fig. 1). Some 35 means is provided for normally keeping the piston and receptacle in such a position with relation to each other that the ports will be closed. As herein shown a spring G engages a part H on the receptacle C and a part I 40 on the handle B. This spring is compressed when the bristles and handle are moved relatively, as shown in Fig. 2, so that when the parts are released they will be returned to their normal position, as shown in Fig. 1. 45 The receptacle C may extend down into the bristles, or there may be provided a discharge tube J, as shown.

When the device is applied to a shaving brush, for example, and it is desired to use 50 the brush, the hollow handle is filled with liquid or other prepared soap. The part containing the bristles is then moved out from the handle, as shown in Fig. 2. This opens the port F and permits a charge of 55 soap to enter the receptacle C. If the part

containing the bristles is now released, the spring will move it back to the position shown in Fig. 1, and the piston D moving in the receptacle C will force a charge of soap into the midst of the bristles of the 60 brush.

It will be observed, of course that some of the elements which I have shown are independent of the functions of others. While I have shown a drawing of what is in effect 65 an operative device, still I desire my drawings to be taken as in a sense diagrammatic. Great changes could be made in the form, shape, size, proportion and arrangement of the parts without departing from the spirit of 70 my invention. What I have shown is the preferred form. I have illustrated the spring as one means for normally drawing the parts together and also for holding them in the retracted position.

I claim:

1. A brush comprising a liquid containing handle, a separate bristle holding member, a tube attached to the bristle holding member projecting into the handle and provided 80 with an opening within the handle, and a piston secured in the handle and projecting into the tube.

2. A brush comprising a liquid containing handle, a bristle holding member, a tube attached to the bristle holding member projecting into the handle and provided with an opening within the handle, a piston secured in the handle and projecting into the tube, the handle and bristle holding member 85 longitudinally movable with reference to each other, and means for holding the bristle holding member in its retracted position 90 against the handle.

3. A brush comprising a liquid containing handle, a bristle holding member, a tube attached to the bristle holding member projecting into the handle and provided with an opening within the handle, a piston secured in the handle and projecting into the tube, 100 the handle and bristle holding member longitudinally movable with reference to each other, and elastic means tending to draw the bristle holding member toward the handle.

4. A brush comprising a liquid containing handle, a separate bristle holding member, a tube open at both ends and attached to the bristle holding member projecting into the handle and provided with an opening in a 110

side wall within the handle, and a piston secured in the handle and projecting into the tube.

5. A brush comprising a liquid containing handle, a separate bristle holding member, a tube associated therewith and extending from within the handle to the bristles, and a piston within the tube.

6. A brush comprising a liquid containing handle, a bristle holding member, a tube having perforated walls associated therewith and extending from within the handle to the bristles, a piston within the tube, the perforations in said tube walls alternately 10 opened and closed by the movement of the piston.

7. A brush comprising a liquid containing handle, a bristle holding member, a tube having perforated walls associated therewith and extending from within the handle to the bristles, a piston within the tube, the perforations in said tube walls alternately 15 opened and closed by the movement of the piston, and a spring which tends to keep the parts together.

8. A brush comprising a liquid containing

handle, a bristle holding member, a tube attached to the bristle holding member and projecting into the handle, a fixed piston in the tube and supported in the handle, and a spring surrounding the tube and interposed between parts on the tube and on the handle.

9. A brush comprising a liquid containing handle, and a tube slidably mounted within said handle and a bristle holding member rigidly mounted upon said tube, a plunger rigidly mounted within said handle, said plunger adapted to enter said tube, said tube connecting with the interior of the handle, a spring surrounding said tube and connected 35 at one end with the handle and at the other with the tube.

10. A brush comprising a hollow handle, a bristle holding member, a tube carrying said bristle holding member and slidably 40 mounted within said hollow handle, and a piston within the handle and adapted to enter said tube.

ALBERT H. ACKERMAN.
